DESIGN FOR A RADIATOR ORNAMENT

Otto M. Wermich, Des Plaines, Ill.

Application July 12, 1934, Serial No. 52,558

Term of patent 3½ years

To all whom it may concern:

Be it known that I, OTTO M. WERMICH, a citizen of the United States, residing at Des Plaines, in the county of Cook and State of Illinois, have invented a new, original, and ornamental Design for a Radiator Ornament, of which the following is a specification, reference being made to the accompanying drawing, forming a part hereof.

In the drawing:—

Fig. 1 is a side elevation of a radiator ornament showing my new design; and

Fig. 2 is a plan view thereof.

What I claim is:—

The ornamental design for a radiator ornament, as shown.

Signed at Chicago, Cook County, Illinois, this 6th day of July, 1934.

OTTO M. WERMICH.
